Primary Examiner — Jae Liang*Assistant Examiner* — Tia Ruth-Renee Polidori(74) *Attorney, Agent, or Firm* — ScienBiziP, P.C.(57) **CLAIM**

The ornamental design for a bullet shaped ear clip, as shown and described.

DESCRIPTION

FIG. 1 is a front, right and top perspective view of a bullet shaped ear clip, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an exploded view thereof; and,

FIG. 10 is a front, right and bottom perspective view thereof, shown with an earring and in a configuration of use for clarity of disclosure.

The portions of the bullet shaped ear clip shown in broken line form no part of the claimed design. The broken line showing of the earring in FIG. 10 depicts environment that forms no part of the claimed design.
